COMB

John W. Killinger, Napa, and Michael C. Demis,
Imola, Calif.

Application October 5, 1950, Serial No. 12,466

Term of patent 14 years

(Cl. D86—8)

To all whom it may concern:

Be it known that we, John W. Killinger, a citizen of the United States and resident of the city of Napa, Napa County, State of California, and Michael C. Demis, a resident of the city of Imola, Napa County, State of California, have invented a new, original, and ornamental Design for a Comb, of which the following is a specification, reference being had to the accompanying drawing, forming a part hereof, and wherein—

I claim:

The ornamental design for a comb, as shown.

JOHN W. KILLINGER.

MICHAEL C. DEMIS.
